UNITED STATES PATENT OFFICE.

JACOB A. HAMELBACK, OF NEWARK, OHIO.

DISH-WASHING MACHINE.

No. 855,570.

Specification of Letters Patent.

Patented June 4, 1907.

Application filed September 24, 1906. Serial No. 336,003.

To all whom it may concern:

Be it known that I, JACOB A. HAMELBACK, a citizen of the United States, residing at Newark, in the county of Licking and State 5 of Ohio, have invented certain new and useful Improvement in Dish-Washing Machines, of which the following is a specification.

My invention relates to improvements in dish-washing machines. Its object, among 10 other things, is to provide for readily effecting such cleansing or washing operation; to accommodate the operative mechanism for successive use in connection with a number of dish-washers proper, thereby increasing 15 the working capacity of the machine; to facilitate the placing and removing of the dishes before and after their cleansing; and to accomplish these ends in a simple, economic and effective manner.

20 Said invention consists of certain structural features or instrumentalities substantially as hereinafter fully disclosed and specifically pointed out by the claims.

In the accompanying drawings—Figure 1 25 is a front elevation of the preferred disclosure of my invention. Fig. 2 is a rear elevation thereof. Fig. 3 is a plan view of the same. Fig. 4 is a vertical central section thereof produced through the vertically adjustable standard, supporting the bracket or frame carrying the dish-washer operating means. Fig. 5 is a view of like character, taken through one of the dish holders and its receiving tank, including the clip-equipped 30 hollow shaft coupled with the latter. Fig. 6 is also a sectional elevation, produced through the contrivance of crane-form for aiding placing and removing the dish-holder with the dishes, before and after the cleansing 35 of the latter.

In carrying out my invention, I suitably provide a table 1, which, together with a contrivance 2 of crane-like form later described in detail, is preferably secured upon a common base board 3.

Two tanks 4, 4, supplied with water, and having cock-equipped pipe-outlets 5, 5, are secured in suspended position in openings in the table 1, above a shallow receptacle 6 50 built into the supporting frame or legs of said table and for receiving the drippings and waste-water from the latter, the waste-water from said pipe-outlets, however, being discharged beyond said drip-receiving receptacle. These tanks are equipped interiorly 55 with vertical ribs or deflectors 7 which serve

to check the otherwise uncontrolled whirling of the water placed in said tanks, and throw it toward the center of said tanks, and thus utilize its action for more effectively cleansing the dishes than would otherwise be the case.

A cylindric open upper ended dish holding cage 8, having an imperforate bottom, and sides formed of spaced apart rods or stout 60 wires secured at their respective ends to said bottom and a top-ring, is adapted to be placed in either of the tanks 4, for receiving the dishes for cleansing. Said dish holding cage, is adapted to centrally receive through 65 its bottom either of two pins or pivots 9, suitably secured to project upward from the bottoms of the tanks 4. The dish holding cage has spanning its upper open end and suitably fixed thereto a yoke 10 having projecting upward centrally therefrom a stud 70 11, preferably angular in outline, as is also especially that part of said yoke in vertical alinement with said stud for a purpose 75 presently apparent.

A handled shaft 12 is suitably journaled in a carrying bracket 13, and has at one end a beveled pinion 14 geared to a corresponding pinion 15, whose tubular shaft 16 is journaled in the same bracket. The tubular shaft 16 80 has its lower end bifurcated as at a with the terminals thus formed slightly spread apart in order to readily receive the upstanding stud 11 of the yoke 10 of the dish-holding cage 8 as also to embrace the alining angular 85 surface of said yoke, and thus provide for coupling said shaft to the latter, for the actuation of the dish-holding cage therefrom. This arrangement also permits of the ready uncoupling of said shaft from said dish-holding cage as will be presently appreciated and for a purpose later noted. Said bracket is 90 itself suitably fixed to an upright cylindric standard 17 whose lower end is let into a socket 18 so as to turn therein, suitably secured upon a fixture projecting from the under side of the drip-receiving receptacle 6, as the preferred way in this instance of assembling these parts. Said standard 17 also passes through a suitably fixed outstanding 95 bar 18', having a hole in it for that purpose, and which bar has secured to its outstanding end preferably a plate 19 having interposed 100 between it and said bar and inserted in a recess in the latter, a bent metal piece or lining 105 20 for said recess. Through the plate 19 and lining 20 is passed a preferably hand-spike

equipped screw 21, working in a nut 22 arranged in said recess, the inner end of said screw being adapted to project into the hole aforesaid and effective to engage and retain 5 said standard in elevated position when that may be required, as later observed.

The crane-like contrivance 2, before referred to, comprises a fixed base 23 and an upper handled member 24, one part thereof 10 forming a beam equipped with pulleys 25 at or in its ends, and its vertical part being pivoted in a socket in the upper end of said base. Over the pulleys 25 and suitably coiled around a drum 26 hung in the handle of the 15 member 24, is a cable 27, from the outer end of which is suitably suspended a hook 28 for engaging with the yoke of the dish-holding cage 8 when it may be desired to conveniently remove the latter with its contents. 20 A pawl and ratchet 29, 30 are suitably provided for the retention against turning of the drum 26 as will be readily understood, said ratchet being fixed to the drum-shaft and said pawl being hung upon the handled member 24. A suitable drain-pipe 31 is supplied to the table 1 the same discharging into the shallow receptacle below.

It is noted that the dishes for cleansing having been suitably loaded into the cage 8 30 of each tank 4 previously removed from the latter to a convenient point for that purpose, and the requisite quantity of water having been supplied to said tanks, the now dish-filled cages may be returned to said receptacles, by bringing into service the crane-like 35 appliance 2 as will be readily appreciated. The handled shaft 12 is now actuated, the coupling having been made between the shaft 16 and the cage 8, when the dish-washing or cleansing operation will be effected. 40 The same having been accomplished, the operative means is disconnected from the cage containing the cleansed dishes and adjusted to the other cage and the same operation proceeded with. The crane-device is now again 45 brought into requisition for effecting the removal of the cage containing the cleansed dishes, and for the refilling or replenishing of this cage, while the operation of cleansing

the contents of the other cage may be taking 50 place, which refilling and cleansing operation may be thus successively conducted.

I claim—

1. A device of the character described, combining a dish-holding cage having a yoke 55 at its upper open end, and actuating means for said cage including a pivoted beam, intergeared shafts carried by said beam one having means adapted to effect connection between it and said yoke and vertically adjusting means for said pivoted beam to permit of uncoupling said yoke-connected shaft, said beam being adapted for lateral movement as in applying said actuating means to a second dish-holding cage. 60

2. A device of the character described, combining a dish-holding cage having a yoke at its upper open end, actuating means for said cage embracing a pivoted beam, intergeared shafts carried by said beam, one of 70 said shafts being equipped for connection with said yoke, a socket receiving the pivoting standard of said beam and a holding screw for the retention of said pivoting standard at the requisite point of adjustment for 75 the disengagement of said yoke-connected shaft. 80

3. A device of the character described, combining a dish-holding cage having a yoke at its upper open end, actuating means for 85 said cage embracing a beam, intergeared shafts carried by said beam, one of said shafts being equipped for connection with said yoke, a pivoting standard for said beam, a socket receiving said standard, an outstanding arm adapted for the passage through it of 90 said standard, and an adjusting screw operative in connection with said arm for the retention of said standard at the requisite point of adjustment. 85

In testimony whereof I have signed my name to this specification in the presence of two subscribing witnesses.

JACOB A. HAMELBACK.
